C. H. SMOOT.

GARMENT FITTING DEVICE.
APPLICATION FILED MAR. 26, 1909.

Patented Feb. 24, 1914.

UNITED STATES PATENT OFFICE.

CHARLES H. SMOOT, OF NEW YORK, N. Y., ASSIGNOR TO RUTH BATTU, OF NEW YORK, N. Y.

GARMENT-FITTING DEVICE.

1,087,992.

Specification of Letters Patent.

Patented Feb. 24, 1914.

Application filed March 26, 1909. Serial No. 486,031.

To all whom it may concern:

Be it known that I, CHARLES HEAD SMOOT, a citizen of the United States, and resident of the borough of Manhattan, city, county, 5 and State of New York, have invented certain new and useful Improvements in Garment-Fitting Devices, of which the following is a specification.

My invention relates to devices for facilitating the accurate fitting of garments.

In principle, my appliance comprises a series of flexible members readily adjustable to different positions so as to fit the person's figure, and removable from the person without changing their adjustment. 15 These flexible members are of a peculiar construction enabling them to be used as clamps or holders for the fabric, so that the same device which has been adjusted to the 20 person's figure, serves to determine the shape of the pieces of fabric composing the garment.

Reference is to be had to the accompanying drawings in which—

25 Figure 1 is a front elevation illustrating the use of my invention; Fig. 2 is a front elevation of one of the flexible members, drawn upon a larger scale; Fig. 3 shows a portion of the two front members and the 30 bands or tapes connected therewith; Fig. 4 shows how the appliance is used in connection with the fabric; Fig. 5 is a cross section on line 5—5 of Fig. 4 and Fig. 6 is a cross section on line 6—6 of Fig. 2.

35 Each of the flexible members comprises two flat pieces or strips A of metal or other flexible but practically inextensible material, the strips diverging at least at one end (see particularly Figs. 4 and 6) but preferably at both ends, as indicated at A'. The 40 two strips are connected and pressed strongly toward each other by means of suitable springs, which I prefer to construct of triangular shape, with one member B in the plane 45 of the strips A, a second member B' at an acute angle thereto, and the third member B² approximately perpendicular to said plane. The coiled portion B³ which gives the spring its chief strength, is located at 50 one of the corners, preferably at the junction of the members B, B². It will be seen that the members B lie in the continuation of one of the flat strips A (to which strip they are secured) and will bear against the 55 garment of the person whom it is desired to

fit; the strips will thus be held in the requisite flat position. The members B' are secured to the companion strips A. Thus the two strips of each flexible member may be separated when desired, yet are pressed 60 toward each other with considerable force so that they form a strong clamp.

Two of the flexible members (which I may call the front members since they are generally used at the front) are provided 65 with detachable connecting means, which may be ordinary corset fasteners as indicated at C, C'.

The several flexible members are connected 70 adjustably by means of transverse flexible but inextensible bands D which may be graduated tapes of the kind used as tape measures. These tapes are fastened permanently to the rear central longitudinal 75 clamping member and are graduated both right and left from such member toward the front (see Fig. 3). These bands or tapes will generally be arranged at three different heights or levels. To hold the tapes adjustably on the flexible members A, A, suitable 80 clamps or retaining members E are provided on said members, the tapes sliding lengthwise and being locked when adjusted, by throwing the clamp levers down.

The number and length of the flexible 85 members will vary with the character of the garment to be produced, each flexible member being intended to be placed where a seam occurs in the garment.

In using my invention, the clamps E are 90 loosened so that the flexible members may be brought to the proper distances from each other, and the entire appliance is placed on the person in the manner illustrated by Fig. 1. The two front members are hooked together, and the other members shifted to right or left, lengthwise of the bands D, until they occupy positions corresponding to the intended location of the seams. Then 95 the clamps are operated to hold the bands and flexible members in their adjusted positions. By unhooking the two front members, the appliance can be released from the person's body without disturbing the adjustment of the parts, that is, the distance between the 100 members connected by the bands D. The appliance is then loaded with the fabric "F" (which may be the main fabric of the garment or only the lining), the quantity of fabric held between adjacent seamholders 105 110

being determined by the length indicated by the longest of the three graduated tape lines.

In loading each of the flexible members or seam-holders, the material may be forced in with a knife by hand, or preferably by drawing the fabric over the edge of the bar "G" (Figs. 4 and 5), which is secured to a board "H", or other suitable support. In this case one of the flexible members, or 10 seam-holders is forced down over the fabric and the edge of the bar "G", thus drawing into the jaws of the seam-holder a fold of the fabric. The diverging ends A' facilitate this operation.

15 After all of the flexible members, or seam-holders, have been filled with a fold of the fabric, the apparatus is again placed on the figure (person or form) to be fitted, the two front members hooked together, and with 20 the fingers all surplus material is drawn into the triangular clearance of the seam-holders until between each two adjacent seam-holders the fabric lies close to the figure to be fitted and all wrinkles or other 25 distortions have been removed. When this process has been completed and the seams extending along the shoulders have been pinned together in a proper location for a shoulder seam, I obtain a perfectly fitting 30 garment, in which the sewed seams are replaced by the flexible seam-holders, which hold the cloth together.

After the above manipulation has been completed and the material molded to fit the 35 figure, the apparatus is removed as a jacket, by unhooking the front members. This material may be pinned along the length of the edge of each of these holders. The seam-holders are then removed and the material is 40 sewed together along the lines originally determined by the seam-holders and located by the pins. The garment is then completed in so far as this appliance is concerned, for a perfectly fitting garment has been obtained and from here on it can be finished 45 by ordinary methods well known to the art.

It will be seen that the spirit of my invention lies in providing a mechanical holder to act in place of a sewed seam, allowing 50 adjustments and alteration in the position of the seam and also in the quantity of the fabric held by the mechanical means. These mechanical means have as their function to hold the cloth after adjustment to a given position and at the same time allow 55 ready alteration of this position. It is obvious that these mechanical means may take many other forms without departing from the spirit of the invention.

60 The strips A form means for connecting and keeping in alignment, a series of clamps or springs, and the strips may therefore be termed alignment members.

Where in the claims I have used "fabric

sections" I refer not only to sections which 65 may be separate and distinct but to sections of fabric before they are cut apart.

While my method of fitting garments will generally be utilized by first cutting the fabric according to patterns of the usual 70 type and approximately to size, I may, without departing from the spirit of my invention, apply the method to an integral fabric not cut into sections. That is to say, I may 75 conform the fabric to the body and shape it to the shape of a fitted garment without passing through the usual intermediate step of cutting the fabric into separate sections according to any pattern.

I claim:

1. In a garment fitting device, a plurality 80 of elongated clamps arranged lengthwise of the body and adapted to be conformed thereto said clamps being further adapted to hold garment sections adjustably, and transverse flexible tapes uniting said clamps.

2. In a garment fitting device, a plurality 90 of elongated clamps arranged lengthwise of the body and adapted to be conformed thereto said clamps being further adapted to hold garment sections adjustably, and transverse flexible tapes adjustably attached to and uniting said clamps.

3. In a garment fitting device, an elongated 95 clamp of inextensible but flexible material adapted to grasp a length of fabric and be conformed to body lines said clamp comprising two faced flexible members in connection with means for pressing said members together.

4. In a garment fitting device, an elongated 100 clamp of inextensible but flexible material adapted to grasp a length of fabric and conform to body lines said clamp comprising two faced flexible members and a plurality of spaced springs for pressing said members together.

5. A garment fitting device adapted to 110 shape and size garment sections upon the body said device comprising elongated clamps adapted to adjustably hold the sections at each vertical seam one of said seams being provided with two clamps lying side by side removably locked together, and transverse flexible tapes adjustably attached to and uniting said clamps.

6. In a garment fitting device, a plurality 120 of elongated clamps arranged lengthwise of the body and adapted to hold garment sections adjustably, each of said clamps being flexible in but a single plane and unyielding in all other planes, and transverse flexible tapes uniting said clamps.

7. In a garment fitting device, a plurality 125 of elongated clamps comprising flat strips of inextensible material adapted to grasp a length of fabric said strips being flexible in a plane normal to their surface and unyield-

ing in all other planes, and transverse flexible tapes adjustably attached to and uniting said clamps.

8. A garment fitting device comprising a plurality of inextensible elongated clamps each consisting of two faced strips held together by spring means and each being flexible in a plane normal to its surface but unyielding in all other planes, transverse flexible tapes for uniting said clamps, and retaining members attached to said clamps for adjustably holding said tapes.

9. A garment fitting device comprising a plurality of inextensible elongated clamps each consisting of two faced strips held to-

gether by spring means and each being flexible in a plane normal to its surface but unyielding in all other planes, a plurality of transverse tapes at different levels for uniting said clamps, and retaining members 20 attached to said clamps for adjustably holding said tapes.

In witness whereof I have hereunto set my hand in the presence of two subscribing witnesses.

CHARLES H. SMOOT.
